UNITED STATES PATENT OFFICE

BAYARD E. RICHARDSON, OF GRAND RAPIDS, MICHIGAN

TYPEWRITER DESK

Application filed May 18, 1925, Serial No. 30,890. Renewed June 30, 1930.

This invention relates to a typewriter desk and is particularly concerned with a desk adapted to hold a typewriter and enclose the same when the typewriter is not in use and with which the typewriter and its support may be projected forward and elevated to a higher level, when the same is to be used, the typewriter being extended in front of the desk and at a height where it is available for use. It is a primary object and purpose of the present invention to make a novel construction of typewriter support and mount the same in a desk in such manner that the same may be projected forward and elevated through motor power and may also be lowered and withdrawn to inner housed position by the same power. A further object of the invention is to make an operating device of this character for the handling of the typewriter and supporting table on which it rests semi-automatic in its action; that is, while the initiation of the movement for the typewriter either from its housed inoperative to operative position, or from its elevated operative position to inoperative position is started by the manual throwing of a switch in an electric circuit, such circuit is broken and the typewriter and its supporting table stopped at the end of either direction of its movement when it reaches a predetermined position, this breaking of the circuit and stopping of the movement occurring automatically.

An understanding of the present invention and the construction embodying the same by means of which these ends are attained, and a practical yet simple operative structure produced may be had from the following description taken in conjunction with the accompanying drawings, in which,

Fig. 1 is a vertical section through a desk pedestal equipped with the invention showing the mechanism in the position it occupies when the typewriter is not in use.

Fig. 2 is a fragmentary perspective view of a detail of structure illustrating the con-

nection of the chain conveyor to the typewriter supporting structure.

Fig. 3 is a view similar to Fig. 1 but showing the supporting structure for the typewriter in its outer elevated operative 50 position.

Fig. 4 is a horizontal section and plan view through the desk pedestal, parts of the construction shown in plan being broken away and shown in section for better disclosure of 55 the construction.

Fig. 5 is a fragmentary enlarged vertical section through the mechanism at one side and adjacent the front of the desk pedestal.

Fig. 6 is a fragmentary enlarged perspective view of the typewriter supporting table and the devices carrying the same, and

Fig. 7 is a diagrammatic outline of the electric wiring system used with the mechanism.

Like reference characters refer to like parts 65 in the different figures of the drawings.

The desk may be of any conventional construction, the pedestal being covered by the usual desk top 1 and each pedestal having a bottom 2, back 3 and vertical spaced apart 70 sides 4, the front of the pedestal being open.

Adjacent the front of said pedestal and on the inner side of each of the sides 4 thereof a vertical channel guide 5 is permanently secured which, at its lower end, may be 75 equipped with a block 6 lying directly above the front portion of the bottom 2 of said pedestal, said block extending into the channel between the flanges thereof. Adjacent the upper end of each channel guide but back 80 thereof an idler sprocket wheel 7 is mounted for rotation, directly below which is a second idler 8 interposed substantially midway between the bottom of the pedestal and said idler 7. Chains 9 run around said idlers. 85

Back of the idlers 8 and substantially in the same horizontal plane are two sprocket wheels 10 around which said chains pass. The wheels 10 are fixed one at each end of a shaft 11 which extends horizontally across 90

the pedestal and is rotatably mounted in suitable bracket supports 12 fixed at the inner sides of the sides 4 of the pedestal, as shown in Fig. 4. A reversible electric motor 13 is rigidly secured to and extends forward from the back 3 of the pedestal, its shaft being extended forward and equipped with a worm 14 which meshes with a suitable worm or tangent wheel 15 fixed on the shaft 11. Said worm and tangent wheel are preferably housed within a housing 16. When the motor 13 is in operation it is evident that the endless sprocket chains 9 which pass around the sprocket wheels 7, 8 and 10 may be continuously driven and as the motor is a reversible motor the chains may be driven in either direction.

Normally located in a plane slightly below the lower run of the sprocket chains 9 is a supporting structure for a typewriter comprising a frame having spaced apart side bars 17 connected at their outer ends by a cross bar 18 and at a point intermediate their ends by a second cross bar 19, a table 20 being secured to the bars 17, 18 and 19 on which the typewriter, shown in dotted outline, may be placed. The bars 17 when within the desk extend a considerable distance back of the cross bar 19 and under the shaft 11. Along side each side bar 17 a channel member 21 is located and permanently secured, the flanges of which extend outwardly from the webs which lie in contact with the adjacent side bars 17.

35 A bracket 22 is attached to each of the side bars 17 and the channel bar 21 lying alongside thereof having a portion extending upwardly which carries a pin 23 permanently connected with one of the links of the adjacent sprocket chain 9. The brackets 22 are located a short distance back of the rear edge of the table 20.

Located at the inner side of each of the vertical channels 5 is a plate 24, substantially triangular in outline, carrying two spaced apart horizontally aligned rollers 25 which are received in the channels 21 previously described. Each plate is formed near its front with an upwardly extending arm 26 which carries an upper roller 27 received in the adjacent channel guide 5, while a lower roller 27 in vertical alignment with the upper roller is carried by the plate at its lower corner and in the housed position of the mechanism the lower rollers 27 bear against the blocks 6. Each of the plates 24 at its front edge and below the table supporting structure for the typewriter is formed with a forwardly extending arm 28 to which hinge members 29 are pivotally connected, the same in turn being attached to the rear side of a door 30 adapted to close the front of the pedestal and being normally yieldingly held in closed position by springs 31 associated

with the hinge connections made by the parts 29 to the plate 24.

With this structure it is evident that with the motor running in one direction and with the typewriter and its support housed within the pedestal, said support is first moved outwardly on the rollers 25 or until the pins 23 pass around the sprocket wheels 8 after which it is elevated, the plates 24 guiding the same by reason of the rollers 27 located within the vertical guide channels 5, and when the upper rollers 27 reach the upper ends of the guide channels 5 the typewriter is located at an upper position and in front of the desk pedestal, as indicated in Fig. 3. When the motor is stopped the construction remains in the position to which it has been moved by reason of the locking against return movement made by the worm and worm gear.

85 The operation of the motor and its automatic stopping is controlled by means of electric agencies, diagram of which is shown in Fig. 7. In this diagram the conductors 32 and 35 are in circuit with a source of 90 electric current such as an ordinary lighting circuit and they lead respectively to the field windings 34 and 36 of the motor 13. Although it is possible to use any type of reversible motor with this device the motor 95 shown and described which is most desirable is of the series wound type and is reversed by reversing the flow of current through the commutator and brushes, thereby changing the polarity of the armature windings relative to the field windings. In the diagram, 100 50 represents the commutator and 51 the brushes. A double-pole double-throw switch is utilized in this circuit, the switch levers 46 and 49 of which are electrically connected 105 with the respective brushes 51 by the conductors 47 and 48. Circuit breakers 40 and 42 are interposed in the circuit for the purpose of stopping the motor when the typewriter support is in either its fully retracted position or fully elevated position. These circuit breakers are operated by the plungers 41 and 43 which are engaged by the rail 17. The contact members 38 and 39 at opposite throws of the double-pole double-throw switch and engaged by opposite switch levers are both electrically connected with the field winding 36 of the motor by the conductor 37, the circuit breakers 40 and 42 being interposed in the circuit, one between 110 each of the switch contact members and the field winding. The oppositely arranged switch contacts 33 and 45 are both in electrical connection with the field windings 34 of the motor, one directly through the conductor 32 and the other through the branch conductor 44 and the conductor 32. In the diagram the switch is shown open.

115 In operation, when the typewriter support is fully housed within the pedestal, as 120 125 130

shown in Fig. 1 and also diagram Fig. 7, the bar 17 engages the plunger 41 and opens the circuit breaker 40 but the circuit breaker 42 is closed and upon closing the switch 5 against the contact members 33 and 38 current flows through the motor, passing through the commutator in one direction and the motor rotates in the direction to move the lower runs of the chains 9 forward 10 carrying the typewriter and its support forward until the connections at 22 and 23 pass around the sprockets 8, after which the typewriter and its support are elevated to the position shown in Fig. 3, whereupon the bar 15 17 engages the plunger 43 of the circuit breaker 42 and breaks the circuit, stopping the motor, and owing to the worm and gear connection between the motor and the shaft 11 the shaft cannot rotate backward and the 20 typewriter and its support are held in this elevated position supported by the chains. Inasmuch as the pins 23, which attach the chains to the typewriter support, will be directly against the upper sprockets 7 in this 25 raised position a large amount of the weight is carried directly by the pins upon the sprockets and the chains relieved of a great deal of the strain.

At the first outward movement of the typewriter support from its fully retracted position, the forward rail 18 engages the door 30 above its pivot point and moves its upper end outwardly and downwardly against the tension of the springs 31 to open the door 35 and as the support continues its outward travel the door is completely opened and disposed substantially horizontal and in almost wholly concealed position beneath the extended support. As the support together 40 with the plates 26, upon which the door is mounted, move upwardly the door also is carried upwardly in this concealed position.

At the first outward movement of the support from its retracted position the plunger 41 of the circuit breaker 40 is released and the circuit is closed at this point, but as the circuit is broken at the double-pole double-throw switch, which is in its opposite position, no current can flow at this side of the switch. 45 To accomplish the reverse operation of the typewriter support and its associated members the operator reverses the position of the switch levers which causes the current to flow through the circuit breaker 40 now closed, and 50 through the motor, passing through the commutator thereof in the opposite direction from that first described, causing the motor to rotate in the reverse direction and the chains reverse their movement lowering the plates 55 26 and carrying the support and door until the plates are stopped and rest upon the blocks 6. The support then moves inwardly with the channels 21 traversing the rollers 25. As the front rail 18 of the support releases the door 60 30 it swings, by virtue of the springs 31, back

to its closed position and at the end of the movement of the support the bar 17 engages the plunger 41 and operates the circuit breaker 40 to break the circuit and stop the motor.

A conventional double-pole double-throw switch is indicated by the diagram but in actuality it is intended to use a switch of the toggle lever or push button type which is designed to accomplish the same result as the switch described, but which is never in open position and this switch is to be located upon the desk at some point where it may be conveniently reached by the operator and is preferably concealed. It will be seen that it is only necessary for the operator to either move the toggle lever or push the button of the switch to accomplish the whole operation of opening the door and extending and elevating the typewriter and its support and stopping the same in the proper position. Likewise to reverse these operations the operator only actuates the switch, whereupon all of the operations of lowering and retracting the typewriter and its support, closing the door and stopping the support within the pedestal are automatically accomplished. If the switch lever should be either intentionally or inadvertently actuated while the typewriter and its support are in mid-position the only effect would be to reverse the motion of the motor and consequently the support and its associated parts and return them to the extreme position where they would automatically stop.

The construction described is relatively simple, not costly to make and is particularly practical and effective in use and operation. The appended claims define the invention which is to be considered as comprehensive of all forms of structure coming within their scope.

I claim:

1. In combination with a desk pedestal, a typewriter support located within the pedestal, means for mounting said support for horizontal and vertical movements, means connected with said support to project said support first forwardly to the limit of its horizontal movement and afterward carry the same upwardly, said means being reversible in operation for returning the support first downwardly to the limit of its vertical movement and thence inwardly to original position within the pedestal, substantially as described.

2. In combination with a desk pedestal, vertical guides located adjacent the front side of the pedestal, means adapted to traverse said guides, a typewriter support mounted for horizontal movement on said means and adapted to be moved horizontally in or out with respect to the pedestal and said means, and means connected to said typewriter support for moving the same first outwardly on said means to the limit of its horizontal movement and afterward elevating

said support with said means whereby the typewriter is carried to an upper position outside of the pedestal.

3. In combination with a desk pedestal, a typewriter support located within the pedestal, means for mounting said support for movement in or out with respect to the pedestal, means for mounting said first means for vertical movement with respect to the pedestal, and means connected with the support whereby, when the support is located within the pedestal and said means operated, the support is first moved outwardly to the limit of its horizontal movement on said first means and said first means is afterward elevated, substantially as described.

4. In combination with a desk pedestal, vertical guides located one on each side of the pedestal adjacent its front side, plates mounted one adjacent each guide and associated with each guide for vertical movements with respect to said guides, a typewriter support located between the plates, means for mounting said support on said plates, for horizontal movements inward or outward with respect to the pedestal, endless chains connected with said support, and means for driving said chains in either direction, whereby, when the support is within the pedestal, the same is first projected outwardly horizontally on said plates and said plates carrying the support therewith are afterward elevated vertically with respect to said guides, and on movement of the chains in the opposite direction said movements of the plates and typewriter support are reversed, substantially as described.

5. In combination, a desk pedestal having an open front side, two vertical channel guides located one on the inner side of each side of the pedestal adjacent said open front, two plates located one adjacent each guide, upper and lower rollers in vertical alignment extending from each plate into its associated guide, a typewriter supporting table located horizontally between the plates, means for mounting said table on said plates for horizontal movements, endless chains mounted one back of each guide, each including a vertical run directly back of the guide, a lower horizontal run extending rearwardly, and an upper downwardly and rearwardly inclined run, sprocket wheels over which the chains pass, connections between the horizontal run of the chains when the typewriter support is within the pedestal and said support, a shaft on which the rearmost sprockets are mounted, and means for driving said shaft in either direction, substantially as described.

6. In combination, two vertical spaced apart channel guides having flanges extending inwardly, a plate located at the inner side of each guide, upper and lower rollers on each plate in vertical alignment located

between the flanges of its adjacent guide, two rollers in horizontal alignment mounted on each plate, a frame having spaced apart side bars and a table between said bars located between the plates, a channel at the outer side of each side bar in which said horizontal rollers on the plates are received, whereby the table may be moved horizontally on said plates, and motor driven means connected with said side bars adapted to move said table from lower horizontal and rear position to an upper forward position or to return the same from said last mentioned position to said first position, substantially as described.

7. In combination with a desk pedestal, a typewriter supporting table housed within said pedestal, an electric motor, means for mounting said table for forward and upward movements or vice versa, means connected to said table and driven by said motor for moving said table, electric circuits associated with said motor, a manually operable switch for closing the circuits and controlling the direction of movement of said motor, and additional switches in said circuits adapted to be engaged and operated so as to stop the motor when said typewriter table has been moved to either lower horizontal position within the desk or upper projected position outside the desk, substantially as described.

8. In a desk pedestal, a typewriter support mounted for movements from a lower position within the desk to an elevated projected position in front of the desk, motor driven means for moving said support from one position to the other or vice versa, two electric circuits associated with said motor, a manually operable switch for completing either circuit, and additional normally closed switches one in each circuit each respectively adapted to be engaged by said support upon movement thereof to its desired position in either direction to thereby break the active circuit and stop the operation of the motor.

9. In combination, a desk pedestal having an open front side, vertical guides located one at the inner side of each side of the pedestal adjacent said open front, a plate mounted on each guide for vertical movements, a typewriter supporting table mounted on and between the plates for horizontal movements, motor driven means attached to said table for moving the same outwardly or inwardly and for moving the plates upwardly or downwardly, and a door pivotally mounted on said plates, the pivots for said door being located below said typewriter supporting table, substantially as described.

10. In combination with a desk pedestal having an open front, a carriage mounted in the pedestal for vertical movements, a typewriter support mounted on said carriage for horizontal movements, a door for the open front of the pedestal hinged to said carriage

below said typewriter support, means for moving the typewriter support outwardly and then moving said carriage upwardly or vice versa, whereby on outward movement of said typewriter support the door is engaged above its pivot and is turned to and held in open position and is carried upwardly by said carriage, and means to return the door to closed position upon reverse movement of the typewriter support and carriage.

10 In testimony whereof I affix my signature.

BAYARD E. RICHARDSON.
